US0D1047886S

(12) **United States Design Patent** (10) Patent No.: **US D1,047,886 S**
(45) Date of Patent: ** Oct. 22, 2024

(54) **SOLAR POWER MODULE**

9/035; H01L 31/042; H01L 31/022425;
H01L 31/18

See application file for complete search history.

(71) Applicants: **VIRIDI E-MOBILITY**

TECHNOLOGY (NINGBO) CO., LTD., Ningbo (CN); **ZHEJIANG ZEEKR INTELLIGENT TECHNOLOGY CO., LTD.**, Ningbo (CN); **ZHEJIANG GEELY HOLDING GROUP CO., LTD.**, Hangzhou (CN)

(72) Inventors: **Ye Yuan**, Zhejiang (CN); **Jia Li**, Zhejiang (CN); **Zequn Yu**, Zhejiang (CN); **Songlin Yang**, Zhejiang (CN); **Yue Ma**, Zhejiang (CN)

(**) Term: **15 Years**

(21) Appl. No.: **35/518,434**

(22) Filed: **Aug. 22, 2023**

(80) **Hague Agreement Data**

Int. Filing Date: **Aug. 22, 2023**

Int. Reg. No.: **DM/231528**

Int. Reg. Date: **Aug. 22, 2023**

Int. Reg. Pub. Date: **Sep. 22, 2023**

(51) **LOC (14) Cl.** **13-02**

(52) **U.S. Cl.**

USPC **D13/102**

(58) **Field of Classification Search**

USPC D10/104.1; D13/101, 102, 103, 107, D13/109, 118, 119, 184, 199; D14/371, D14/432, 439, 441, 447, 451; D21/480, D21/484; D25/109, 140, 144

CPC .. F21S 8/086; F21S 8/088; F21S 9/032; F21S

(57) **CLAIM**

The ornamental design for a solar power module as shown and described.

DESCRIPTION

1.1 : Perspective

1.2 : Front

1.3 : Back

1.4 : Left

1.5 : Right

1.6 : Top

1.7 : Bottom

1.8 : Perspective

1.9 : Unfolded

Purpose of this design product: the present design product is used to collect sunlight and convert light energy into elec-

(Continued)

trical energy; design point of this design product: the shape of the design; picture or photograph that best embodies the design point of this design: fig. 1.1; the dash-dash broken lines in the drawings depict the portions of the solar power module which form no part of the claimed design.

1 Claim, 9 Drawing Sheets
